(57) **CLAIM**

The ornamental design for a friendship bracelet maker, shown and described.

DESCRIPTION

FIG. 1 is a top perspective view of the friendship bracelet maker showing my new design;

FIG. 2 is a top plan view thereof;

FIG. 3 is an end view thereof;

FIG. 4 is an opposite end view of FIG. 3;

FIG. 5 is a right side view thereof;

FIG. 6 is a left side view thereof; and,

FIG. 7 is a bottom plan view thereof.

The broken lines shown in the figures form no part of the claimed design.
